CHARM FOR BRACELET OR THE LIKE

Bertha S. Wolfe, 6154 W. 76th St.,
Los Angeles, Calif. 90045

Filed July 27, 1970, Ser. No. 23,147

Term of patent 14 years

Int. Cl. D11—01

U.S. Cl. D45—17

FIG. 1 is a front elevational view of a charm for bracelet or the like showing my new design;

FIG. 2 is a side elevational view from the right side of FIG. 1;

FIG. 3 is a rear elevational view;

FIG. 4 is a side elevational view from the left side of FIG. 1;

FIG. 5 is a top plan view; and

FIG. 6 is a bottom plan view.

I claim:

The ornamental design for charm for bracelet or like, substantially as shown.
